GIN BREAST FRONT MOUNTING

Frank E. Deems, Birmingham, Ala., assignor to
 Continental Gin Company, a corporation of
 Delaware

Application March 6, 1939, Serial No. 259,974

9 Claims. (Cl. 19—56)

My invention relates to a new and improved mounting for the fronts of huller gins.

Huller gins are customarily provided with elements defining a front hulling chamber and an inner roll box, the seed cotton being delivered by a cotton slide from any suitable distributor and feeder means into the hulling chamber where it is brought into engagement with the saws which carry the seed cotton into the roll box to 5 form a roll from which the saws act to strip the lint from the seed.

The gin breast has a front closure which it has been customary to mount so that it can be taken down and removed from the gin when there is 10 occasion to have full access to the hulling chamber for repairs, inspection, or any other purpose.

The manner in which the breast front has been made demountable heretofore has been satisfactory enough for gaining access to the gin breast 15 for repair or inspection, because that did not have to be done with any great rapidity, but in the operation of a battery of gins occasions do arise when it is of great importance that deflectors can be quickly moved so as to form shunt doors 20 adapted to intercept further delivery of cotton into the gins. For instance, should a fire start in the distributor, through which cotton is being fed to a battery of gins, it is important, if the fire is to be controlled, that the burning cotton 25 in the distributor should be discharged therefrom as rapidly as possible, but it is obviously equally important that this burning cotton should not be discharged into the hulling chamber of the gins of the battery being fed from such distributor.

Under such circumstances my invention is 30 designed to permit a breast front to be swung almost instantaneously from its normal vertical position forming a front closure for the hulling chamber to an inwardly inclined position across the hulling chamber in which it is adapted to 35 deflect further feed of cotton from the gin out onto the floor of the gin house where it could be readily and promptly extinguished without igniting cotton in the gin from where fire might 40 pass on into the condenser and press. With the fronts so arranged, the delivery of the cotton from the distributor need not be interrupted and the burning cotton can be rapidly run out and 45 dumped onto the floor in front of the several gins of the battery.

My invention further contemplates providing 50 the breast front with upper and lower relatively movable mounting means which are adapted 55 to permit its complete detachment from the gin

or its partial release which will permit it to be moved rearward about its lower mounting elements as a pivot until it falls against the roll box and is thereby supported in position to deflect, through the opening provided by its displacement, further delivery of cotton from the cotton slide to its respective gin.

My invention further contemplates mounting the breast front by means of upper and lower pins in suitable guide slots provided in the end frames 10 of the gin which are so designed that the upper pins will clear their retaining slots well in advance of the lower pins clearing their slots, thus freeing the upper end of the front to be swung inwardly on its lower guide pins as pivots to 15 assume feed-intercepting position.

My invention further contemplates so designing the upper slots in which the top pins are received that a rapid upward movement of the front to disengage it therefrom will give it a 20 thrust rearwardly so that it will fall automatically into its feed-intercepting position when released.

My invention further contemplates taking advantage of the lower pins remaining engaged in their slots after the upper pins have cleared their 25 respective slots, to swing the front outwardly and downwardly to full open position and gain access to the roll box without dismounting the front from the gin.

My invention further contemplates designing 30 the upper and lower mounting slots so that the lower slots extend upwardly and then open to the front while the upper slots extend upwardly and rearwardly and open toward the rear, the lower slots being of substantially greater dimension 35 vertically than the upper slots.

My invention further comprises the novel details of construction and arrangements of parts which, in their preferred embodiment only, are exemplified in the accompanying drawing which forms a part of this specification, and in which:

Fig. 1 represents a vertical transverse cross section view through the upper portion of a huller gin with the breast front shown in full lines in its "feed-intercepting" position, and in 40 dotted lines in both its normal and its full open positions.

Fig. 2 is a detail view in front elevation, of the breast front in its normal working position, broken away to show the slots for its mounting 45 pins at one end in vertical cross section.

Similar reference numerals refer to similar parts throughout the drawing.

I have shown my invention associated with a huller gin comprising a roll box 5 in its inner 55

breast 6 and a hulling chamber 7 in its outer breast 8. The seed cotton is delivered normally into the hulling chamber by means of a cotton slide 9 from a feeder supplied by an overhead distributor, the feeder and distributor not being shown as they form no essential part of my invention. The gin comprises the customary grate fall 10 and hulling ribs 11 with both of which the saws 12 coat, the latter ribs being attached 10 overhead to a rib rail 13 carrying the lower roll box front 14 with which a movable roll box door 15 is associated. The outer breast 8 is pivotally mounted on the pins 16 which are engaged in slots 17 at the forward edges of the inner breast 15. A breast front 18, of any standard construction, closes the front of the gin and has end frame members 19 provided each with an upper mounting pin 20 and a lower mounting pin 21, which pins are mounted fixedly so as to project 20 horizontally beyond the ends of the front. Each upper pin is received in a slot 22 formed in a frame member 23 offset inwardly from the inner face of the adjacent head of the outer breast 8, and these slots 22, as will be seen in Fig. 1, lead 25 upwardly at a rearward inclination and open through the top of said member 23, thus permitting them to be lifted up and out of their slots by a relatively short up-movement of the front 18.

The lower pins 21 work in slots 24 formed in 30 the lower end of the offset members 23, these slots being vertically elongated and opening at their upper end outwardly through the front edge of the members 23, as will be seen more clearly in Fig. 1. The pins 21 normally rest in the lower 35 ends of the slots 24 and form pivot supports for the front 18 which is held in normal vertical operating position by the engagement of its top pins 20 in the shallow slots 22. The breast front is shown provided with an offset 25 extending 40 across its upper edge to serve as a handle or grip to manipulate the front.

Assuming the front 18 mounted in its vertical dotted position (Fig. 1), which is its normal operating position, and the feed of seed cotton falling 45 from the slide 9 in the hulling chamber 7, it will be apparent that if fire starts in the conveyor or distributor system, or any other objectionable or dangerous condition arises making it desirable to intercept feed to the gins without necessarily 50 either stopping the gins or the conveying and distributing mechanism, this is quickly and easily effected as follows. An operator moving swiftly along the battery of gins, grasps each breast front 18 by its offset 25 and gives it a quick upward 55 jerk. This lifts the pins 20 clear of the slots 22 but does not lift the pins 21 clear of the slots 24. The rearward inclination of the slots 22 gives to the free upper portion of the front a tilt or thrust toward the rear so that when it is released it will 60 fall rearwardly across the hulling chamber 7 against the roll box door 15, and form an outwardly and downwardly inclined chute which will divert all material, thereafter falling from the slide 9, outwardly onto the floor in front of the 65 gin. An operator can accomplish this shift of the front so quickly that it will hardly require more time than for him to traverse the battery of gins. Thus all the gins can have their feed quickly and completely intercepted by elements 70 that are fire proof in themselves.

If it be desired entirely to remove the breast front, it is only necessary to lift it far enough for both sets of pins to clear their respective slots, in which case it can be set aside and replaced as 75 easily as it was removed.

If it be desired to gain access to the hulling chamber and interior of the gin without removing the front, it can be lifted only high enough for its pins 20 to clear the upper slots 22 and then it can be swung over forwardly and downwardly to the lower dotted position shown in Fig. 1, in which it will hang open from said lower pins 21 out of the operator's way while he gives the necessary attention to the mechanism within the gin, after which the front can be swung up and set in place by engaging its pins 20 in their slots 22. This is the simplest way to handle the breast front when it is desired to gain access from the front of the gin into the roll box 5, or to correct any trouble in the lower portion of the hulling chamber.

The pin and slot manner of connecting the front to the gin breast is probably the simplest and least expensive, but my invention is not to be restricted thereto as releasable upper and lower latch means or sliding or movable connections may be used, provided they and the gin are designed to allow the breast when freed overhead to be swung inwardly across the hulling chamber 15 to form a feed deflector.

To prevent the lower pins 21 jumping out of their slots when the front is jerked up, I prefer to incline the top wall 26 of each slot 24 upwardly and rearwardly sufficiently to form a pocket at the upper end of each slot adapted to catch and hold the pins, when they strike these walls 26, from jumping out of the slots and entirely dismounting the front from the breast.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are 40 specifically set forth in the appended claims.

What I claim is:

1. In a huller gin, a hulling chamber, a cotton slide for delivering cotton into said chamber, and a front for said chamber comprising releasable means normally holding it in its operative position, said front being so mounted and said chamber so designed that the front may be swung inwardly across said chamber to deflect the entering cotton outwardly from the gin.
2. A gin having a breast front with upper and lower mounting projections at each end, upwardly extending guides in the gin to receive said projections, the upper guides being constructed and arranged to permit the complete disengagement of the upper front projections therefrom and the gin being arranged to permit the breast front thus partially freed to swing inwardly across the path of cotton and the like being fed to the gin into position to deflect same from the gin.
3. In a gin according to claim 2, in which the lower projections are also demountable from their respective guides, thereby to permit the complete removal of the breast front from the gin.
4. A gin according to claim 2, in which the gin is free of obstructions that would prevent the breast, when its upper projections are free of their respective guides, swinging outwardly and downwardly on its lower projections as pivots engaged in their respective guides.
5. A gin according to claim 2, in which the upper guides are inclined upwardly and rearwardly.
6. A gin according to claim 2, in which the upper guides are inclined upwardly and rear-

wardly, and the lower guides are disposed vertically and adapted to open to the front.

7. In a huller gin having a hulling chamber, a roll box and a feed chute delivering material into the hulling chamber, a breast comprising a movable front wall for said hulling chamber, and means to mount said wall so that it may be rocked inwardly across the hulling chamber into position against the roll box so as to intercept and outwardly deflect the material being fed to the gin.

8. A huller gin having elements defining a hulling chamber and roll box, the latter comprising a movable door to give access to the roll box, means to feed the material to be treated into the hulling chamber of the gin, a front for said chamber having lower movable connections and top latch elements and constructed and arranged when said top elements are disengaged from the

gin to be swung on its lower connections either inwardly across the hulling chamber into position to intercept the further feed of material thereto, or outwardly so as to hang down and afford full access to the hulling chamber and door of the roll box.

9. In a huller gin having wall members defining a hulling chamber, overhead means to deliver cotton and the like into said chamber for treatment, and a front wall element, movably mounted to define a front opening for said hulling chamber, said element being arranged and mounted for ready displacement inwardly across the path of the cotton entering said hulling chamber and into position to effect the immediate discharge of such entering cotton from the gin through said front opening.
